UNITED STATES PATENT OFFICE.

OSCAR W. JOHNSON, OF ROCKFORD, ILLINOIS, ASSIGNOR TO WARD-LOVE PUMP CORPORATION, OF ROCKFORD, ILLINOIS, A CORPORATION OF ILLINOIS.

CLOSURE OPERATOR.

Application filed January 5, 1925. Serial No. 474.

This invention relates to closure operators adapted for application to a cap or closure element for a filling pipe or tube or for any orifice in a similar member whether 5 for filling or discharging purposes. The present application of my invention is to the filling pipe of a tank or container and, more particularly, to a tank such as is used in water softening apparatus.

10 One of the objects of my invention is to provide an improved closure for a filling pipe in which the closure cap is not threadedly connected to the pipe but seats preferably against a gasket, and in which fastening means is employed to clamp the cap in the closing position and to release it, which means is threadedly engaged on the pipe and connected with the cap to impart rectilinear movement for seating it rather 20 than to impart rotative movement which might impair or injure the gasket.

Another object is to provide in a device or structure of the character described means for guiding the screw threaded 25 clamp, especially when entering it onto the threaded pipe; also to provide a spray nozzle for spraying or distributing water into the tank as will be described more fully hereinafter.

30 Still another object of my invention is to provide a practical and satisfactory means for closing the filling orifice in the top of a water softener tank of the kind used for household purposes and the like as distinguished from large capacity apparatus 35 used for industrial purposes. The orifice referred to is used for filling the tank with the base-exchange material such as zeolites, also for introducing salt for the purpose of 40 regeneration. To this end it is necessary to have a comparatively large diameter filling pipe with which the ordinary and conventional cap and closures cannot be satisfactorily used. The present invention provides, 45 however, a very effective means for closing a filling orifice of this kind and at the same time providing a satisfactory means for spraying or distributing water into the top of the tank when regenerating.

50 Other objects and attendant advantages will be appreciated by those skilled in this art as the invention becomes better understood by reference to the following descrip-

tion when considered in connection with the accompanying drawing, in which— 55

Figure 1, is a vertical sectional view through a screw-threaded closure operator embodying my invention;

Fig. 2, is a top view thereof; and

Fig. 3, is a horizontal section taken on the line 3—3 of Fig. 1.

The present application of my invention is to the filling pipe neck or tube 4 on the top of a tank or container 5. An annular closure cap 6 is adapted to seat on an end surface of the pipe 4 for closing the orifice therein. A suitable gasket 7 is interposed between the cap 6 and seat 8 on the pipe, the gasket being retained in a recess 9 in the underside of the cap. 70

A clamp threadedly engaged on the periphery of the pipe 4 is employed for clamping the cap against its seat and likewise for withdrawing the cap therefrom. This clamp comprises a nut element 11 and having integral therewith and extending upwardly therefrom a diametrically disposed yoke 12 which overlies the cap 6 and has a centrally disposed depending pressure-exerting point 13 which engages in a complementary recess 14 in the top of the cap. The clamp may be turned by any suitable means, either by grasping it directly or by the aid of a tool. I prefer, however, to provide one or more handles 15 fixed to the clamp, a most effective arrangement being to locate the handles on diametrically opposite sides as shown, whereby a very powerful leverage advantage is obtained in combination with the threaded mounting of the clamp. 80

To the underside of the cap 6 is attached or suitably applied means for functioning both as a guide and a spray nozzle or distributor. In the present embodiment of my invention this comprises an annular gasket retainer 16, a perforated disc 17, a plurality of ribs 18 interposed between the parts 16 and 17 for holding them in spaced relation, and a bolt 19 passing through said parts with its head bearing against the underside of the said part 17 and its threaded end engaged in the cap so as to clamp said parts and likewise the gasket to the underside of the cap 6. 90

A water supply pipe 21 enters the filler pipe 4 above the disc or nozzle 17 so that the 100

105

water supply delivered into the pipe 4 will be sprayed or distributed into the tank below by reason of the perforations in the disc 17. The small perforations or orifices 22 in the disc 17 are shaped so that the water will be discharged in a spray-like delivery in a diverging spray so as to distribute the water over a larger area than that of the filler pipe 4 to aid in dissolving the salt and 10 secure more uniform distribution of the solution.

In the particular use of my improvement herein disclosed it will be observed that the cap 6 is firmly clamped in the closing position by the clamp which has been pulled or turned down, the clamping pressure being centrally applied by a rectilinear movement to the center of the cap so that it will be held seated by a uniform application of pressure 20 circumferentially about the seat. In this position the nut element 11 is spaced below the cap a distance indicated by 23 (Fig. 1). Thus when removing the cap the clamp may first be loosened and then unscrewed quite 25 rapidly so that the nut element will strike the lower edge of the cap with such force as to unseat it. This forceful lifting blow is desirable since in some cases after long usage the cap is somewhat corroded or stuck to 30 the seat and considerable pressure is required to remove it. After the nut element of the clamp has been unscrewed from the pipe 4, the clamp, cap and parts attached thereto by the bolt 19 may be lifted from 35 the pipe orifice to permit filling the tank with zeolite or salt as the case may require. When replacing the parts it will be observed that the disc 17 by contact with the inner wall of the pipe will constitute a guide in 40 that it positions the cap 6 in proper alignment with the pipe; and by reason of the close contact between the periphery of the cap and the adjacent arms of the yoke and by contact of the cap against the nut 45 element 11 the latter will be located in proper alignment with the threaded end of the pipe 4 so as to properly engage the threads thereof, thus facilitating entrance of the nut onto the threaded part. When 50 the cap is clamped down in position as described, water may be delivered into the top of the tank through the pipe 21 and will be sprayed and distributed by the interposition of the disc 17 which functions as a spray nozzle. It will be observed that when tightening the clamp considerable pressure may 55 be exerted on the cap without turning it and consequently without injuring the gasket.

It should be understood that my invention 60 is applicable to a cap closure for any pipe or similar member having an orifice either for filling or discharge purposes. I have, therefore, used the term "pipe" or "neck" in the claims as meaning any member of this character.

It is believed that the foregoing conveys a clear understanding of the objects prefaced above and while I have illustrated but a single working embodiment it should be understood that in different applications of my invention changes might be made in details of construction and arrangement of parts within the scope of the invention as described in the appended claims, in which—

I claim:

1. In combination, an externally threaded pipe, a closure cap adapted to seat thereon and equipped with guide means extending into the pipe to cooperate with the internal wall thereof, and a clamp threadedly engaged on said pipe and having means for engaging opposed sides of the closure cap, whereby to clamp the cap against its seat when the clamp is turned in one direction and to withdraw the cap from said seat when turned in the opposite direction, the cap being so closely associated with the clamp that said guide will serve to hold the clamp in operative relation to the pipe threads when entering the clamp onto the pipe.

2. A device of the character described comprising, in combination, a tank having an externally threaded filler pipe, a closure cap seated on said pipe, a clamp threaded on the pipe for clamping the cap to seat it when turned in one direction and to remove it from its seat when turned in the opposite direction, a perforated disc carried by and spaced inwardly from the cap, and a fluid inlet opening in the pipe intermediate the cap and perforated disc.

3. A device of the character described, comprising in combination, an externally threaded pipe, a closure cap adapted to seat on the pipe to close the orifice therein, and an operator for said closure cap arranged either to jam the cap against its seat or remove the same therefrom, said operator comprising an internally threaded portion for threaded engagement with the pipe and an integral yoke portion extending across the outside and over the top of the cap and joined at its ends to the threaded portion, whereby to provide a side opening for entering the cap in the operator, said operator being arranged to jam the cap against its seat by engagement of its yoke portion with the top of the cap when the operator is threaded onto the pipe and being arranged to force the cap off its seat by engagement of its threaded portion with the under side of the cap when the operator is threaded off the pipe.

4. In a device as set forth in claim 3, the provision of a bearing between the yoke portion of the operator and the top of the closure cap comprising a conical projection on one of the said members, and a depression to receive the same provided in the

other of said members whereby the cap is rendered self-aligning with respect to the end of the pipe and is borne against centrally when jammed into sealing engagement with the end of the pipe.

5. A device of the character described comprising, in combination, an externally threaded pipe, a cap adapted to seat against the pipe for closing the orifice therein, a 10 one-piece clamp having a nut portion threaded on the pipe and a yoke extending diametrically across the outside of the cap and joined at its ends to said nut portion, and diametrically opposed handles on the 15 clamp in alignment with said yoke, whereby when the clamp is turned in one direction the yoke will bear against the cap for clamping it to its seat and when turned in the opposite direction the nut portion will bear 20 against the other side of the cap for removing it from its seat.

6. A device of the character described comprising, in combination, an externally threaded pipe, a closure cap adapted to seat 25 on the pipe to close the orifice therein, and an operator for said closure cap arranged either to jam the cap against its seat or remove the same therefrom, said operator comprising an internally threaded nut portion 30 for threaded engagement with the pipe, and an integral yoke portion extending across the top thereof and joined at its ends to the nut portion whereby to provide a recess for the cap between the yoke portion 35 and the nut portion, the cap having its edges overlying the nut portion of said operator and being disposed beneath the yoke portion whereby the operator is arranged to jam the cap against its seat by engagement

of its yoke portion with the top of the cap 40 when the operator is threaded onto the pipe and is arranged to force the cap off its seat by engagement of its nut portion with the under side of the cap when the operator is unthreaded from the pipe.

45 7. In combination, a tank having an externally threaded filling pipe, a closure cap seated against said pipe, a fluid distributor within said pipe attached to the inner side of the cap and spaced therefrom toward the 50 inner end of the pipe, the filler pipe having a fluid inlet opening intermediate the cap and said distributor, and a clamp threadedly engaged on the pipe for clamping the cap in the closed position.

55 8. The combination set forth in claim 7, including a gasket interposed between the cap and pipe, and means for holding the gasket in position against the cap including a bolt which serves also to hold the distributor in position on the cap.

60 9. A device of the character described, comprising in combination, a pipe, such as the filling pipe of a tank, a cap for closing the orifice in the pipe, a gasket providing a 65 seat against which the cap is arranged to be clamped, a gasket retainer for holding the gasket against the cap, a perforated distributor plate, spacing means between said gasket retainer and said plate, a bolt for 70 fastening said plate to said cap to hold the cap, gasket retainer, spacing means and plate assembled together, and means for clamping the cap in position closing the orifice in the pipe, said pipe being provided 75 with a fluid inlet opening between said distributor plate and cap.

OSCAR W. JOHNSON.
